ROAD GRADING APPARATUS

Howard H. Samuel, Hackettstown, N. J.

Application January 13, 1932. Serial No. 586,306

10 Claims. (Cl. 37—108)

This invention relates to improvements in road grading machinery; and the invention has reference, more particularly, to a novel construction of machine especially adapted for the final preparation of the subgrade of roadways preparatory to laying concrete pavement thereon.

This invention has for its principal object to provide a novel road subgrader having selectively usable scarifying means and scraping means, both said means being adjustable for depth of cut; and, furthermore, the subgrader is provided with a novel construction of traction means designed to run on the metal forms, as laid to receive cast concrete slabs of pavement, in such manner that both the scarifying means and scraping means may, when set for a given adjustment, be maintained throughout the grading operation at the proper level to assure the exact depth of cut, whereby a uniform even depth of grade will be established and thereby an exact and correct thickness of concrete slab produced, when the concrete mix is cast upon the prepared subgrade and between the side forms.

This invention has for a further object to provide a novel construction of subgrader of the kind and for the purposes above mentioned, which may be operated by drawing the same with a road rolling machine, so that grading and rolling can be accomplished in one operation.

Another object of this invention is to provide a novel construction of subgrader having selectively usable and adjustable scarifying and scraping means so arranged that the same may be controlled for both use and for adjustment by a single operator.

Other objects of this invention, not at this time more particularly enumerated, will be understood from the following detailed description thereof.

An illustrative embodiment of this invention is shown in the accompanying drawings, in which:—

Fig. 1 is a front elevation of the novel subgrader according to this invention as operatively mounted to run on concrete casting forms, and as arranged for the use and operation of the scarifying means thereof; Fig. 2 is a similar view, showing the subgrader as arranged for the use and operation of the scraping means thereof; Fig. 3 is a vertical longitudinal section, taken on line 3—3 in Fig. 2; and Fig. 4 is a plan view of the subgrader apparatus.

Fig. 5 is a detail view, in part section, showing one of the adjustable lateral guide rollers of the machine which cooperate with the concrete casting forms, and which serve to hold the machine,

when operated, against lateral shifting or displacement relative to said forms; and Fig. 6 is a detail horizontal section of the same, taken on line 6—6 in Fig. 5.

Fig. 7 is a front view of the subgrader, showing the connection therewith of detachable traction means with which the same may be provided, and which serve as a convenient means for transporting the machine from job to job; Fig. 8 is a detail side elevation of a detachable journal element and transport wheel which form said detachable traction means; and Fig. 9 is an exterior end elevation of said journal element.

Similar characters of reference are employed in the above described views, to indicate corresponding parts.

Referring now to the drawings, the reference character 10 indicates the side chassis beams of the machine frame-work. Secured to and upon, and extending transversely between said chassis beams 10 at the front end of the machine are a pair of longitudinally spaced bolster beams 11; and arranged in like manner at the rear end of the machine is a third bolster beam 12. Secured to and upon the bolster beams 11 and 12, and extending longitudinally from front to rear of the machine in a substantially central position is a bed beam 13. Similar longitudinal bed beams 14 are arranged in laterally spaced relation to opposite sides of said central bed beam 13. Secured to and upon said bed beams 13—14, adjacent to the rear end of the machine, is a transversely extending bridge beam 15. The various beams above described constitute the frame-work or carriage body of the machine, and said beams may be suitably secured together by any suitable form of fastening means, although I have found it very satisfactory to fasten the same in assembled relation by the process of electric welding, which provides integral joints between the parts wherever the same meet.

The chassis beams 10 are respectively provided adjacent to their forward and rearward ends with bearing members 16 in which are journaled the axle portions of traction wheels 17. Said traction wheels 17 may be arranged and mounted adjacent to either the inner or outer sides of said chassis beams, according to the conditions governing the particular job, as will be subsequently again referred to. The traction wheels are initially gauged or transversely spaced apart at distances to correspond to the laterally spaced relation of laid metallic concrete forms 18 between which a first course of concrete pavement slabs are to be cast during road

building operations, whereby the machine carriage or frame-work may laterally straddle said forms, while being supported by the traction wheels 17 for longitudinal movement upon and 5 along said forms.

In order to prevent displacement of the frame-work or carriage of the machine and the traction wheels 17 thereof relative to the forms 18, when moved over and along the latter, guide 10 means are mounted on the frame-work or carriage to engage and cooperate with the inner faces of the forms 18. One such guide means is located adjacent to and inwardly of each traction wheel 17. Each guide means comprises a 15 vertical shaft 19, which is securely clamped to the outer face of an adjacent bolster beam, 12 or 13 as the case may be, by means of a U-clip 20, which embraces the shaft 19, and the legs of which pass through the body of the bolster beam, 20 whereby the same may be secured to the latter by nuts 21 which screw upon the free ends of 25 said legs. The lower end of the shaft 19 is provided with a diametrically enlarged lateral annular flange 22 (see Fig. 5) to support the lower ends of a plurality of anti-friction rollers 23 disposed around the lower end portion of the 30 shaft. A guide roller 24 is mounted on the lower end portion of the shaft 19 to freely rotate thereon and upon the anti-friction rollers 23. If 35 desired the lower open end of the guide roller 24 may be closed by a bottom cover plate 25 suitably secured thereto, and which serves to keep dirt and other foreign matter from gaining access to the interior of the anti-friction bearing 40 elements serving said guide roller. The flanges of the bolster beam, at the points where a guide- 45 roller shaft 19 is connected therewith, are provided with indented semi-circular seats 26, and the shaft is provided with reduced portions 27 eccentric to the axis thereof. Said eccentric portions 27 are engaged respectively in the seats 26. By reason of this arrangement adjustments of 50 the guide roller 24 toward and from the inner face of a form 18 may be easily made by axially turning the shaft in one direction or the other to turn the eccentric portions 27 in the seats 26, thereby moving the guide roller 24 inwardly or outwardly as may be necessary in order to assure proper engagement of said guide roller with the 55 face of the form 18 without tendency to crowd or tip the latter. The guide rollers 24, when in use will bear against the inner faces of the forms 18 so as to keep the traction wheels 17 running 60 straight upon the tops of the forms, and the machine properly centered over the road surface between the forms which is to be graded. The 65 guide rollers 24 may be arranged to bear on the form faces at any desired point intermediate the top and bottom portions of the latter. If arranged to bear low down on the form faces, that is toward the bottom portions of the latter, there will be less likelihood of risk of over-tipping the forms. The kind and structural character of the forms themselves will readily indicate the 70 best point to be engaged by the guide rollers 24. The scarifying means of the machine is located at the forward end of the same, and comprises the following arrangement. Secured to the bolster beams 11, parallel to and spaced inwardly 75 from the sides of the outer bed beams 14 are angle irons 28, which together with the bed beams 14 and the spaced bolster beams 11 provide vertical guideways in which are disposed vertically movable carrier members 29. It is preferable 80 to cut away the body of the central bed beam

13 to provide a guideway for a similarly arranged vertically movable central carrier member 29. Suitably secured to the lower ends of said carrier members 29, so as to extend transversely of the machine, is a V-shaped holder comprising 85 the upwardly and rearwardly inclined back-plate 30 and the upwardly and forwardly inclined front-plate 31. Mounted upon the upper face of said back-plate 30, with their lower ends extending through said front-plate 31, and projecting downwardly and forwardly beyond the outer surface of the latter, are a plurality of laterally spaced scarifying teeth 32, having chamfered chisel-like ends. These teeth are reversible end for end, and can be removed from the holder, reversed, and reinserted therein when first used ends become too worn. The teeth are rigidly held in secured relation to the holder by means of a clamp-strap 33 adapted to overlie 90 the upper end portions of the teeth, said clamp-strap 33 being secured by bolts 34 to the back plate 30 of said holder. Journaled in and extending between bearings 35 secured upon the bed beams 14, and extending through a central housing 36 fixed on the central bed beam 13, is 95 a shaft 37. Fixed on said shaft 37 within the housing 36 is a segmental or quadrant gear 38. Journaled in bearings 39 fixed on the top of said housing 36 is a longitudinal power shaft 40, the same extending rearwardly through a 100 bearing standard 41 mounted on the bridge beam 15 so that its rearward end is located adjacent to the rear end of the machine. Fixed on the rearward end of said power shaft 40 is a hand 105 wheel 42 for manually applying power thereto. Fixed on said power shaft 40 is a worm 40' which engages said segmental or quadrant gear 38, whereby power applied to shaft 40 in either direction is transmitted to shaft 37. Secured to 110 said shaft 37 respectively adjacent to the outer carrier members 29 are lever arms 43, the free ends of which are connected by links 44 to said carrier members. Adjustable stop-screws 45 are threaded into the angle irons 28 so as to lie 115 in the path of downward swinging movement of said lever arms 43. By adjusting the height of 120 said stop-screws 45 the downward movement of the carrier members 29 and the scarifying means supported thereby may be selectively predetermined to in turn determine the depth of cut 125 to be made by said scarifying means when lowered to operative position.

The scraping means of the machine is located at the rearward end of the same, and comprises 130 the following arrangement. Pivotedly connected by suitable hinge knuckles 46 to the rearward bolster beam 11 are laterally spaced apart rearwardly extending carrier arms 47 having downwardly curved free ends. Suitably mounted on the forward faces of the curved free ends of 135 said carrier arms 47 to extend transversely of the machine is a concavo-convex scraper plate 48, with its concave face forwardly presented. Extending along the back of said scraper plate 48 is a reinforcing rib 49, which may be made of angle iron welded or otherwise secured to the body of said scraper plate. Suitably secured to the lower marginal portion of said scraper plate 44 is a toe-plate 50 of hardened steel and having its lower free working edge suitably sharpened. Secured to and upon the bridge beam 15 are laterally disposed housings 51 respectively outwardly off-set in opposite directions from the longitudinal center of the machine. Each housing 51 is provided at its upper end with spaced 140

bearings 52 in which is journaled a power shaft 53, having a hand wheel 54 on its inward end for manually applying power thereto. Mounted on pivoting shafts or journals 55 extending transversely through said housings 51 are segmental or quadrant gears (not shown) which are similar to the quadrant gear 38 of the above described scarifying means. These gears have outwardly projecting lever arms 56 connected to move therewith. Fixed on each power shaft 53 is a worm 57 to engage and transmit to said quadrant gears the power applied to said shafts 53. The pivoted scraper plate structure is connected at its opposite end portions by links 58 with the free ends 15 of the respective lever arms 56. Connected respectively with opposite end portions of the scraper plate structure are upwardly projecting stop-rods 59, the free ends of which slidably pass upwardly through said bridge beam 15. The 20 upper free ends of said stop-rods 59 are threaded to receive stop-nuts 60, which are thus vertically adjustable thereon. Also threaded upon said stop-rods 59 are jamb nuts 61 to cooperate with said stop-nuts 60 so as to lock the same 25 in selected desired adjusted position on said stop rods. By setting the stop-nuts 60 in properly adjusted position, the distance of the operating edge of the toe-plate 50 from the top of the forms 18 may be exactly predetermined when 30 the scraper plate is lowered to operative position, and consequently the exact level of the finished subgrade surface relative to the tops of the forms may be assured, so that no waste occurs by casting any excess of concrete when 35 laying pavement slabs thereof. It will be observed that each end of the scraping means is individually controlled by its own raising and lowering means and its corresponding stop means, and consequently the scraping means 40 may be nicely adjusted to produce subgrades having lateral pitch or declination for producing crowned pavement.

Secured to the bolster beam 12 by brackets 62 is a platform 63 upon which the operator of the 45 machine may stand in order to manipulate the hand wheels for selectively bringing the scarifying and scraping means into and out of service, as may be required during the operation of the machine.

The machine is adapted to be drawn during 50 operation thereof by any suitable draft means. Preferably, however, the machine is connected with a power grade roller as a trailer thereto, whereby grading and rolling may be accomplished in one operation. A novel self-compensating coupling means is provided which so functions that a true straight pull upon the grading machine is assured regardless of any given path of travel taken by the hauling roller. This novel coupling 55 means comprises a V-shaped draft yoke 64, the respective arms of which are pivotally connected, as at 65, to the forward bolster beam 11. Pivotally coupled, to turn in horizontal plane, with the forward apex end of said draft yoke 64, is a draft-link 66. Mounted in connection with the forward end of said draft-link are a pair of grooved rollers 67-68 which respectively engage opposite sides of a transverse draft bar 69 which is connected with the rear end of a roller, tractor or other hauling means by suitable off-setting brackets or frame supports 70.

In the use of the machine for preparing a sub-grade upon which is to be cast a first course of concrete slabs, the forms 18 are set to correct 75 grade along each side of the course. The forms 18 being set, the grading machine is mounted thereon so that the traction wheels 17 thereof ride on the tops of said forms, with the guide rollers 24 adjusted to bear against the inner faces of the forms so as to hold the machine against lateral displacement and so that the same runs true along the forms. The grading roller or other hauling means is now coupled through the described draft appliances with the machine, and the operator takes his station on the platform 63 ready to control the operations of the machine. If it is desired to scarify the surface between the forms which is to be graded, the operator manipulates the hand wheel 42 to lower the scarifying means to operative position, whereby the teeth 32 are brought into operative relation to the earth. If the scarifying operation is to be separately performed, the scraping means is raised to inactive position. It is frequently possible to perform both the scarifying operation and the scraping operation at the same time, in which case the scraping means is lowered to a selected adjusted position according to the depth of sub-grade desired. As the grading roller or other hauling means is moved forward, the trailing 80 grading machine follows thereafter and is pulled straight and true through the described draft coupling devices, any lateral deviation or off-set path of travel of the grading roller or hauling means being automatically compensated for by 85 corresponding movement of the draft bar 69 between the rollers 67-68 of the draft link 66, so that a constant straight pull without lateral deviation is transmitted to the grading machine, and consequently no over turning pressure is 90 exerted by the guide rollers 24 on the forms 18. The scarifier teeth 32 will, as they are advanced, 95 dig into the subsurface so as to efficiently loosen the soil and break down high spots therein. The 100 downwardly and rearwardly inclined front plates 31 of the holder of the scarifier teeth will operate to downwardly deflect loosened soil so that the same is passed rearwardly between the teeth and behind the scarifying means to lie in front of the scraping means; at the same time any larger stones dislodged from the soil, and not capable of 105 passing between the teeth 32, will be rolled ahead along the surface. The operator can readily manipulate the scarifying means to raise and 110 lower the same as conditions may require while the machine is being advanced. Since the scraping means is rearward of the scarifying means, the soil loosened by the latter lies in the path of the former, so that the toe-plate 50 will scrape and spread the same evenly at the true subgrade 115 level, any excess soil being tumbled ahead by the concave surface of the scraper plate 48, until the accumulation thereof becomes sufficient to be released, whereupon the operator may actuate the 120 hand wheels 54 to raise the scraper plate, and thus deposit the excess accumulated soil in one place ready for removal; again lowering the scraper plate for continued operation as the machine proceeds. From the above it will be apparent that scarifying, scraping and rolling of 125 the subgrade may be performed in one operation, thereby saving considerable time and labor. If conditions warrant, however, either the scarifying or scraping means may be alone employed 130 at any stage of the work.

In operating the machine preparatory to laying a second course of concrete to abut or laterally adjoin a first laid course, the forms 18 at the inner side of the first laid course are removed, 140 and an outer run of forms are erected paralleling 145

the first course of finished concrete. The grading machine is then mounted so that the traction wheels 17 at one side thereon run on the outer run of forms while the traction wheels at the opposite side run on the surface of the finished concrete. Inasmuch as it is desirable to have the latter traction wheels bear upon the finished concrete well within or back of its edge, so as to avoid risk of chipping such edge, the journals of the traction wheels 17 are reversible in their bearings 16 so that the same may be located on the exterior side of the chassis beam instead of the inner side as shown in the drawings. When so reversed the traction wheels 17 will bear on the top surface 15 of the finished concrete well back from its edge, while the adjacent guide rollers 24 will nevertheless bear on the exposed side face of the laid concrete slabs. The scarifying and scraping operations are thereupon carried on in the same manner as already described as the thus mounted grading machine is advanced along the work.

From the above description it will be obvious that the level of the moving grading machine is determined by the set forms 18, and consequently 25 is constant relative to the forms. It therefore follows that if the scraping blade is set to given depth below the form tops, the produced sub-grade will be accurately produced and fixed at such depth without variation therefrom. Not only 30 will the produced subgrade be uniformly run, but the same may be predetermined by the setting of the scraping plate to the exact point desired. This is of great importance since it eliminates the waste consequent upon casting concrete slabs of 35 thicknesses in excess of contract specifications which results from excessive cutting down of subgrade levels, and which frequently occurs when subgrades are prepared by hand or by machines running on ground surface. It has been 40 estimated that in most concrete road work the finished slabs average over an eighth of an inch in excess of required specified thicknesses, for which excess the contractor receives no compensation although being penalized for deficient thicknesses. An excess of an eighth of an inch in 45 a twenty foot road would consume about 41 cubic yards of concrete per mile, which at an average cost of approximately six dollars per yard would involve a loss of nearly \$250.00 per mile. The saving of this loss alone illustrates the advantages 50 to be gained by accurate subgrading as it can be accomplished by the novel construction of grading machine according to this invention as above described.

As a further part of the instant invention means are provided for facilitating the transportation of the novel grading machine from place to place where its use is required. To this end there is provided a pair of detachable journal brackets adapted to be affixed to and intermediate the ends of the exterior bolster beams 11-12, upon which may be rotatably mounted transport traction wheels 71 for movably supporting the machine so that it can be towed from place to place. Each such journal bracket comprises a clip-plate 72 having an undercut rib 73 at one side. This clip-plate is disposed under a bolster beam with said rib 73 hooked over the bottom flange at the inner side of the beam. Integral 70 with said clip-plate 72 is boss 74 from which projects a journal portion 75 to receive the hub of the traction wheel 71. Bolts 76 are passed through said clip-plate and boss with their heads overlapping the bottom flange of the bolster beam 75 at the outer side thereof. Integral with and ex-

tending upwardly from said clip-plate is a bracing stay 77 the upper free end of which abuts the top flange at the outer side of the bolster beam, thus bracing the clip-plate and its rib 73 from undue strain.

As many changes could be made in the above described construction, and many apparently different embodiments of the invention could be made without departing from the scope thereof, it is intended that all matter contained in the above description or shown in the accompanying drawings shall be interpreted as illustrative and not in a limiting sense.

I claim:—

1. In a machine for subgrading between forms preparatory to casting concrete paving slabs, a frame-work having traction means to ride on said forms, a scarifying means vertically movable in connection with said frame-work to active or inactive positions, pivoted lever arms for lowering and raising said scarifying means, means for actuating said lever arms, and vertically adjustable stop screws mounted on said frame-work to lie in the path of said lever arms and adapted to stop downward movement thereof to thereby selectively limit the active position level of said scarifying means.

2. A machine for subgrading between forms preparatory to casting concrete paving slabs, comprising a frame-work having traction wheels to ride on the tops of said forms, guide rollers mounted in connection with said frame-work to bear laterally against side faces of said forms, a manipulatable toothed scarifying means adjacent to the forward end of said frame-work to extend transversely between said forms, adjustable means to selectively position the effective toother edge of said scarifying means for operation at a predetermined depth below the tops of said forms, a manipulatable scraping member adjacent to the rearward end of said machine to extend transversely substantially throughout the space between said forms, and adjustable means to selectively position the effective scraping edge of said scraping member for operation at a predetermined depth below the tops of said forms.

3. A machine for subgrading between forms preparatory to casting concrete paving slabs, comprising a frame-work having traction wheels to ride on the tops of said forms, guide rollers mounted in connection with said frame-work to bear laterally against side faces of said forms, a manipulatable toothed scarifying means adjacent to the forward end of said frame-work to extend transversely between said forms, adjustable means to selectively position the effective toothed edge of said scarifying means for operation at a predetermined depth below the tops of said forms, a manipulatable scraping member adjacent to the rearward end of said machine to extend transversely substantially throughout the space between said forms, adjustable means to selectively position the effective scraping edge of said scraping member for operation at a predetermined depth below the tops of said forms, and means accessible at the rear end of said frame-work for selectively manipulating said scarifying means and said scraping member at will.

4. In a machine for subgrading between forms preparatory to casting concrete paving slabs, a frame-work having traction wheels to ride on the tops of said forms, guide rollers mounted in connection with said frame-work to bear laterally against side faces of said forms, and means

- to adjust said guide rollers relative to said form faces.
5. In a machine for subgrading between forms preparatory to casting concrete paving slabs, a frame-work having traction wheels to ride on the tops of said forms, said frame-work having rotatively adjustable dependent shafts, guide rollers at the lower portions of said shafts, said shafts having means to laterally shift the same 5 when rotatively adjusted to dispose said guide rollers to engage side faces of said forms, and means to fix said shafts in given laterally adjusted positions.
6. In a machine for subgrading between forms preparatory to casting concrete paving slabs, a frame-work having traction wheels to ride on the tops of said forms, said frame-work rotatively adjustable dependent shafts, guide-rollers having anti-friction bearings mounted on the 10 lower portions of said shafts, said shafts having eccentric portions, said frame-work having seats to receive said eccentric portions, and means to secure said shafts in given rotatively adjusted positions whereby said guide rollers are disposed 15 to engage side faces of said forms.
7. In a machine for subgrading between forms preparatory to casting concrete paving slabs, a frame-work having bearing portions on its opposite longitudinal sides, and traction wheels 20 having journal members mounted in said bearing portions, said traction wheels and journal members being reversibly relative to said bearing portions to selectively dispose said traction wheels at either the inner or outer ends of said bearing 25 portions, said traction wheels being adapted to ride on the tops of said forms to movably support the machine in bridging relation across the same.
8. In a machine for subgrading between forms 30 preparatory to casting concrete paving slabs, a carriage to travel on the tops of said forms in bridging relation thereto, means to retain said carriage against lateral displacement relative to said forms, a scarifying means mounted on said carriage to extend between said forms, means to raise and lower said scarifying means to inactive or active position, and means to selectively position said scarifying means for operation at a predetermined depth below the tops of said forms, said scarifying means including a holder of V-shaped cross-section, a plurality of downwardly and forwardly inclined laterally spaced scarify- 35 ing teeth projecting from said holder, and the upwardly and forwardly inclined face of said 40 holder serving to deflect loosened soil rearwardly through spaces between said teeth while operating to roll forward and separate from said loosened soil relatively large stones and rubble. 45
9. In a machine for subgrading between forms preparatory to casting concrete paving slabs, a carriage to travel on the tops of said forms in bridging relation thereto, means to retain said carriage against lateral displacement relative to said forms, a scarifying means mounted on said carriage to extend between said forms, means to raise and lower said scarifying means to inactive or active position, and means to selectively position said scarifying means for operation at a predetermined depth below the tops of said frames, said scarifying means including a holder of V-shaped cross-section, a plurality of laterally spaced sharp ended reversible scarifier teeth, and means to clamp said teeth to the inner face of the rearwardly inclined wall of said holder with their free operative ends projecting downwardly and forwardly through said forwardly inclined wall of said holder. 50
10. In a machine for subgrading between forms preparatory to casting concrete paving slabs, a carriage to travel on the tops of said forms in bridging relation thereto, means to retain said carriage against lateral displacement relative to said forms, said carriage having a platform for stationing an operator at its rearward end, a scarifier means at the forward end portion of said carriage comprising a holder to extend between said forms having a plurality of downwardly and angularly directed laterally spaced scarifier teeth, means on said carriage to raise and lower said scarifier means including a power shaft and hand-wheel accessible from said rear platform, adjustable stop means for predetermining the working level of said scarifier means, a scraping means at the rearward end portion of 55 said carriage comprising a concavo-convex scraper plate to extend between said forms having a sharpened toe-plate at its lower margin, means on said carriage to raise and lower said scraper plate including independently movable carrying means connected respectively with opposite end portions of said scraper plate and power shafts for respectively actuating said carrying means each having a hand-wheel accessible from said rear platform, and adjustable stop means for predetermining the working level of said scraper plate. 60
